[57] CLAIM

The ornamental design for a sewing machine, substantially as shown and described.

DESCRIPTION

FIG. 1 is a front elevational view of a sewing machine showing my new design;

FIG. 2 is a rear elevational view;

FIG. 3 is a left side elevational view;

FIG. 4 is a right side elevational view;

FIG. 5 is a top plan view;

FIG. 6 is a bottom plan view;

FIG. 7 is a front, top and left side perspective view; and

FIG. 8 is a view similar to FIG. 7 with the handle in raised position.
